UNITED STATES PATENT OFFICE.

JOHN W. REED, OF CHICAGO, ILLINOIS.

PIANO-STRING BRIDGE.

SPECIFICATION forming part of Letters Patent No. 338,779, dated March 30, 1886.

Application filed January 31, 1885. Serial No. 154,507. (No model.)

To all whom it may concern:

Be it known that I, JOHN W. REED, a citizen of the United States of America, residing at Chicago, in the county of Cook and State 5 of Illinois, have invented certain new and useful Improvements in Piano-String Bridges, of which the following is a specification, reference being had therein to the accompanying drawings.

10 My invention relates to an improved bridge for pianos and other stringed instruments.

The object of the invention is to so construct such bridges as to improve the tone of the wires passed over them; and to the accomplishment of that end the invention consists 15 in the novel combination of parts, as will be described and claimed.

Reference will be made to the accompanying drawings, in which Figure 1 is a plan in 20 detail showing a section of the instrument; and Figs. 2, 3, sectional detail views of the bridges.

Like letters refer to like parts in each view.

25 A represents a section of the sounding-board, B the strings, and C the wrest-plank. Upon the wrest-plank are mounted the tuning-pins D, the agraffe E, and my improved bridge F. This bridge is formed of glass. I have, however, illustrated in the drawings two forms 30 and arrangements which I think will be found advantageous.

In Fig. 2 the wrest-plank C is represented as formed with a depression or socket, into

which the bridge is inserted and held. The body of this bridge is formed of glass and 35 provided upon its upper face with a transverse groove or depression, in which a metal bar, a, is placed, the wires when in position resting directly upon bars a.

In Fig. 3 I have represented the bridge as 40 triangular in cross-section, with the wires resting upon its upper pointed surface.

In either of these constructions the bridge may be mounted in a suitable frame, G, mounted upon the wrest-plank. By either of the 45 arrangements shown it will be seen that the points of contact between the wires and the bridge are as small as possible; and it will be understood that the tones produced will be greatly improved by having the strings rest 50 at one end upon such a bridge as described, and at the other end upon any suitable bridge.

I am aware that glass bridges have been used, and also that a metal bar embedded in a bridge has been used.

55 What I claim is—

The combination, with a bridge made of glass, of a metal bar or wire embedded in the same, as set forth.

In testimony whereof I affix my signature in 60 presence of two witnesses.

JOHN W. REED.
